UNITED STATES PATENT OFFICE.

EDWIN T. MARBLE AND EDWIN H. MARBLE, OF WORCESTER,
MASSACHUSETTS.

MACHINE FOR WAXING VELVETS, &c.

SPECIFICATION forming part of Letters Patent No. 478,236, dated July 5, 1892.

Application filed January 25, 1892. Serial No. 419,126. (No model.)

To all whom it may concern:

Be it known that we, EDWIN T. MARBLE and EDWIN H. MARBLE, citizens of the United States, residing at Worcester, in the county of Worcester and State of Massachusetts, have invented a new and useful Machine for Waxing Velvets, Plushes, and other Pile Fabrics, of which the following, together with the accompanying drawings, is a specification sufficiently full, clear, and exact to enable persons skilled in the art to which this invention appertains to make and use the same.

The object of our present invention is to provide in a machine for waxing fabrics a revolving bar-wax carrier and facilities for supporting and adjusting the fabric in proper relation for receiving the wax therefrom in greater or less quantity uniformly upon the surface of the fabric; also, to provide efficient means for dampening and cooling the wax surfaces in proper degree to obviate the excessive softening of the same by friction or by variations of temperature.

Another object is to improve the general construction of the mechanism and to render the machine convenient, efficient, and desirable for use.

These objects we attain by mechanism the nature, construction, and operation of which is explained in the following description, and illustrated in the drawings, the particular subject-matter claimed being hereinafter definitely specified.

In the drawings, Figure 1 is a central longitudinal section at line $x-x$ (the lower left corner showing the side) of a fabric-waxing machine constructed in accordance with our invention. Fig. 2 is a half-vertical section and half-front view of the same. Fig. 3 shows the adjustable roll-bearing support for the apron.

Our invention comprises a revolving wax-carrier composed of a series of recessed bars or long radially-hollowed boxes or pockets arranged at the periphery of suitable spiders or wheels, in connection with a rotatable shaft or axis arranged to turn in suitable bearings on the supporting-frame and having a driving-pulley or means for imparting rapid rotary motion to the carrier. Said recessed bars

or boxes form receptacles for containing long flat bars of wax and are provided with suit-

able plates and screws or devices for clamping the bar-wax in place and for adjusting the same outward as the wax wears away by its distribution upon the fabric. In combination with this wax-carrier we provide a swinging fabric-supporter over which the fabric is passed and which has mounted thereon a guide and a holdback roll, whereby the fabric can be strained with a greater or less degree of tension and its surface thus presented to the revolving carrier, while the fabric is fed forward with a constant movement.

Our invention also comprises means for quickly relieving the fabric from the waxing action and for varying the fabric tension and the quantity of wax applied to the pile-surface thereof.

Our invention further comprises, in combination with the wax-carrier, an improved cooling and dampening apparatus having a flexible traveling apron that is suspended in a manner to properly wipe the edge of the wax bars as the carrier revolves, the said apparatus being provided with adjustable bearings for the apron-supporting rolls to afford greater or less pressure in its action on the wax, also with facilities for advancing this cooling-apron at required speed.

Minor features of improvement will be noted in explaining the construction of our invention, which we will now proceed to describe more in detail.

In the drawings, A denotes the frame; B, the feed-roller covered with card-clothing; C, the wax-carrier composed of the spiders or end wheels C', fixed on the shaft C² and having the wax-carrying bars or boxes c, rigidly attached to the peripheries of said wheels, as indicated. In the present instance five of said bars are employed, but more or less in number can be used, as in any instance desired. The shaft C² is provided at one end with pulleys C³ for the driving-belt and at the other end with pulleys a and b for operating the brush and feeding-roll mechanism, the belts and gearing for which are not herein shown, but may be of any suitable kind for transmitting the motion and power to the parts operated thereby.

D indicates the pieces of wax material, which are best formed in long flat bars of rect-

angular section about one and one-eighth inch (more or less) in thickness and of any desired width adapted to set into the recess of the carrier-bar *c* flatwise or so as to project therefrom radially and present its edge to the work. The bar of wax *D* is securely held within the carrier-pocket by a plate *d* and set-screws *e* at one side thereof, and an edge-plate *d'* and set-screws *e'* are provided for adjusting and supporting the bar-wax with the proper amount of projection at the periphery.

F indicates a movable frame or fabric-supporter pivoted at *f* to a stationary part and adapted to swing toward and from the wax-carrier. A card-toothed holdback-roll *G* is journaled in bearings on the side bars at the front part of said supporter and a guide bar or roll *F'* is disposed parallel therewith in bearings or ears near the rear part of said supporter, said rolls *G* and *F'* being about equidistant from a plane perpendicular to the supporter and passing through the axis of the carrier *C*. A friction-brake *g*, having a binding-screw or means for adjusting the pressure of the same, is provided for controlling the resistant action of the holdback-roll *G*, and thereby regulating the tension on the fabric, which is spread and strained taut across the space from the roll *G* to the roll *F'* and its surface there presented to the action of the wax-bars, which strike the flexible part of the fabric midway between the said rolls.

H indicates a shaft having cams *h*, whereon the swinging end of the fabric-supporter *F* is sustained and by means of which the same can be adjusted nearer to or farther from the wax-carrier. A hand-wheel *H'* is arranged on the outer end of said shaft to facilitate rotation of the cams, and a ratchet-wheel *h*² and pawl *h*³ are provided for locking the shaft and cams at position of adjustment. A stop-finger is best arranged on the cam-shaft to engage with a lug fixed on the frame, as at *j*, to prevent rotation of the cams beyond their normal limit of action.

J *J* indicate guiding-rolls for directing the fabric, the course over which the fabric travels through the machine being indicated in Fig. 1 by the dash-and-dot line *W*.

K indicates the cooling-apron, which is arranged above the wax-carrier and mounted upon guiding-rolls *K' K'*, by which it is suspended at a position where the edges of the wax *D* will come into contact with its extended central part as the wax-carrier revolves, so that the apron wipes and cools the rubbing-edge of the wax and prevents the softening of the same from heat caused by friction on the pile of the fabric or by atmospheric temperature. The bearings *i* of the rolls *K'* are pivoted or adjustably attached to the main frame, so that the rolls *K'* can be depressed or elevated to cause the apron to bear with greater or less force or for a longer interval upon the wax bars *D*. A take-up roll *K'*², mounted in adjustable bearings *k*, is arranged within the apron for increasing or diminish-

ing the tension thereof, as desired. For dampening, the apron passes between two rolls—a drive-roll *L* and presser-roll *L'*—mounted in bearings at the top of the frame, and said drive-roll runs in a trough *M*, containing water or other dampening material. The drive-roll *L* is operated by a belt *n* on its pulley *l* from the intermediate pulleys or change-wheel *m*, running on a stud or axis near the lower part of the frame, which pulley is in turn actuated by a belt *n'* from a pulley *m'* on the wax-carrier shaft *C*. Hence a continuous advance motion is imparted to the apron *K* from the carrier at a speed which can be proportionally varied by varying the sizes of the intermediate or change wheels *m*, as required.

P indicates the revolving brush for working the wax into the pile of the fabric, and *O* the bed-roll for supporting the fabric adjacent to the brush. Said roll is journaled in swinging bearing-arms *r*, connected with a rocker-shaft *R* and a toothed segment and worm-screw *r'*, and a hand-wheel *R'* is provided for adjusting said roll *O* toward or from the brush to give greater or less effective action on the fabric or to accommodate fabrics having different depths of pile.

T indicates a swinging tail-guide to discharge the fabric in folds.

In the operation the fabric is drawn through the machine in the direction indicated and the wax-carrier is revolved, bringing the wax bars *D* successively into contact with the pile on that part of the fabric which is flexibly sustained by being drawn taut between the holdback-roll *G* and supporter-bar *F'*, and wax is thus laid upon the face of the fabric in a very uniform, efficient, and desirable manner, the quantity deposited being varied, as desired, by adjusting the supporter *F* by aid of the cam-shaft and cams *h* nearer to and farther from the wax-carrier.

By our invention we provide a machine that can be practically operated at much higher degree of speed than can be successfully done with machines as heretofore constructed, while the mechanism is more conveniently and effectively adapted to the requirements of the work and by it the wax can be uniformly and satisfactorily laid upon the pile in heavy or light quantity, as may in any instance be desired.

It will be understood that we do not broadly claim a rotatable waxing mechanism irrespective of construction, as we are aware that revolving cylinders of wax have heretofore been employed, but of different construction from our improved mechanism. Neither do we broadly claim the use of an endless dampening-apron in a waxing-machine otherwise than in the improved arrangement and combination as herein described.

We claim as our invention herein, to be secured by Letters Patent—

1. The combination of the revoluble wax-carrier composed of a series of separate bars

- rigidly supported by wheels or spiders on a central rotatable axis and each adapted for holding a bar of wax and a fabric-supporter provided with two rolls or supports whereon the fabric is flexibly sustained by being drawn tightly across an unobstructed space between said two supports and there presented to the action of said revoluble wax-carrier, for the purpose set forth.
5. The combination, substantially as described, of the rigid cylindrically-revoluble wax-carrier having the recessed bars or peripheral pockets with facilities for holding bars of wax therein, an adjustable fabric-support having thereon the holdback-roll and a guide-roll respectively disposed at its front and rear with an intervening space and adapted for extending and presenting the fabric flexibly sustained across said space to the face of said wax-carrier, means, substantially as described, for adjusting said fabric-support toward or from the wax-carrier, and an adjustable brake for varying the tension of said holdback-roll, for the purpose set forth.
10. 2. The combination, substantially as described, of the rigid cylindrically-revoluble wax-carrier having the recessed bars or peripheral pockets with facilities for holding bars of wax therein, an adjustable fabric-support having thereon the holdback-roll and a guide-roll respectively disposed at its front and rear with an intervening space and adapted for extending and presenting the fabric flexibly sustained across said space to the face of said wax-carrier, means, substantially as described, for adjusting said fabric-support toward or from the wax-carrier, and an adjustable brake for varying the tension of said holdback-roll, for the purpose set forth.
15. 3. The combination of the revoluble carrier C, having rigidly-attached wax-supporting bars and means for securing and adjusting bars of wax supported thereon, the swinging fabric-carrier F, having the guide-roll F², and the holdback-roll G, mounted thereon, and guide-rolls J at front and rear thereof, said rolls arranged for straining the fabric across the face of the carrier, and the shaft H, with cams h beneath the free end of said supporter, the hand-wheel H' for moving the same to swing the supporter toward and from said carrier, and the ratchet h² and pawl h³, for the purpose set forth.
20. 4. In a fabric-waxing machine, the wax-carrier, bars or wax-boxes rigidly fixed to the periphery of spiders or end wheels, mounted on the rotatable shaft, said boxes having the radially-disposed longitudinal pockets or recesses therein provided with plates d and d', and screws e and e' for binding and radially adjusting the bars of wax, substantially as described, in combination with the fabric-supporter and means for advancing the fabric across the same, for the purpose set forth.
25. 5. The combination, substantially as described, of the revoluble carrier having recessed bars or peripheral pockets with facilities for holding bars of wax therein, the adjustable fabric-supporter having thereon a holdback-roll and a guide-roll for extending and flexibly presenting the fabric to the ac-
- tion of said wax-carrier, the revolving endless cooling-apron, the apron-guiding rolls at front and rear of said wax-carrier, the dampening-rolls, and means for advancing the apron, for the purposes set forth.
6. The combination of the revoluble bar-wax carrier, the cooling-apron K, the guide-rolls K', whereby said apron is extended and supported over the wax-carrier, and the roll-supporting bearings i, attached to and adjustable on the frame for raising and lowering said guide-rolls and apron in relation to the wax-carrier, substantially as and for the purpose set forth.
7. The combination, substantially as hereinbefore described, of the revoluble bar-wax carrier C, having the pulley m² on its shaft, the endless apron K, its guide-rolls K', the dampening and drive roll L, having the pulley l fixed on its axle, intermediate pulleys or change-wheels m, and belts n and n' for transmitting relative motion from the carrier-axis to said apron, for the purpose set forth.
8. The tension-regulating roll K² and its adjustable bearing-supports k and the endless apron K, its adjustably-supported guiding-rolls K', in combination with the revoluble bar-wax carrier C, fabric-supporter, and feeding mechanism, substantially as and for the purpose set forth.
9. The combination, substantially as described, of the revoluble bar-wax carrier C, the endless traveling apron K, its guide-rolls K', and dampening-rolls L, the adjustable fabric-supporter F, with fabric-guide F² and holdback-roll G, the adjustable friction-brake for said holdback-roll, the rotatable brush P, its adjustable bed-roll O, the feed-roll B, and guide-rolls J, relatively disposed for operation in the manner shown, and for the purposes set forth.
10. The revolving brush P, the fabric-supporting roll O, the adjustable arms r, having said roll mounted thereon, the rocker-shaft R, connecting said bearing-arms, the toothed segment and worm-screw r', and the operating hand-wheel R², in combination with a wax-carrier and fabric supporting and feeding mechanism, substantially as set forth.
- Witness our hands this 22d day of January, 105
A. D. 1892.
